(57) **CLAIM**

I claim the ornamental design for a increased length and diameter shaped golf club grip, as shown and described.

DESCRIPTION

FIG. 1 is a front elevation view of the increased length and diameter shaped golf club grip showing my novel design;

FIG. 2 is a rear plan view thereof;

FIG. 3 is a left side elevation view thereof;

FIG. 4 is a right side elevation view thereof;

FIG. 5 is a top elevation view thereof;

FIG. 6 is a bottom elevation view thereof; and,

FIG. 7 is a perspective view thereof.

The broken lines showing in FIG. 7 is for illustrative purposes only and forms no part of the claimed design.
